DESIGN FOR LACE

Hage W. Hucknall, Douglaston, N. Y., assignor to The American Lace Mfg. Co., Elyria, Ohio, a corporation of Ohio

Application August 16, 1939, Serial No. 86,730

Term of patent 3½ years

To all whom it may concern:

Be it known that I, Hage W. Hucknall, a citizen of the United States, residing at Douglaston, in the county of Queens and State of New York, have invented a new, original, and ornamental Design for Lace, of which the following is a specification, reference being had to the accompanying drawing, forming a part thereof. The figure is a plan view of a section of the lace, showing my new design, the repeat unit of which is contained between the horizontal dot and dash lines and the vertical dot and dash lines.

I claim:

The ornamental design for lace, substantially as shown and described.

HAGE W. HUCKNALL.
